UNITED STATES PATENT OFFICE.

JAMES H. HOPKINS, OF POMONA, CALIFORNIA, ASSIGNOR TO JESSE MCCOMAS
AND CHARLES W. GOODWIN, BOTH OF POMONA, CALIFORNIA.

DESIGN FOR A VAPORIZER FOR INTERNAL-COMBUSTION ENGINES.

59,592.

Specification for Design.

Patented Nov. 8, 1921.

Application filed June 28, 1920. Serial No. 392,520. Term of patent 14 years.

To all whom it may concern:

Be it known that I, JAMES H. HOPKINS, a citizen of the United States, residing at Pomona, in the county of Los Angeles and State of California, have invented a new, original, and ornamental Design for a Vaporizer for Internal-Combustion Engines, of which the following is a specification, reference being had to the accompanying drawing, forming part thereof.

Figure 1 is a front elevation of my new design.

Fig. 2 is a rear elevation of Fig. 1.

Fig. 3 is a plan view of Fig. 1.

Fig. 4 is an inverted plan view of Fig. 1.

The essential feature of my design consists in providing in a vaporizer for internal combustion engines of the character indicated in the drawing, a cylindrical body of transparent material having heads at its opposite ends, one of said heads terminating in a frusto-conical portion.

Having thus described my invention, I claim:

The ornamental design for a vaporizer for internal combustion engines, substantially as described and shown.

Signed at Los Angeles, California, this 18th day of June, 1920.

JAMES H. HOPKINS.
